UNITED STATES PATENT OFFICE.

GEORGE M. BRANT, OF HAMILTON, ILLINOIS.

CIRCUIT CLOSER FOR RAILROAD-CROSSING SIGNALS.

Application filed October 12, 1922. Serial No. 594,057.

To all whom it may concern:

Be it known that I, GEORGE M. BRANT, a citizen of the United States, residing at Hamilton, in the county of Hancock and 5 State of Illinois, have invented certain new and useful Improvements in Circuit Closers for Railroad-Crossing Signals; and I do declare the following to be a full, clear, and exact description of the invention, such as 10 will enable others skilled in the art to which it appertains to make and use the same.

This invention relates to an improved circuit closer for use in connection with a railroad crossing signal and one object of the 15 invention is to provide a circuit closer which may be connected with one of the rails and set in operation by vibration caused when a train is moving along the track and approaching the crossing. It is well known 20 that when a train is moving along a track, the rails will be caused to vibrate for some time before the train reaches a given crossing and it is desired to make use of this vibration in order to cause closing of a circuit and thereby cause a bell, light or any other electrically operated signal to be energized and thus attract attention.

Another object of the invention is to so construct this device that it may be clamped 25 firmly against the web portion of one of the rails where it will be out of the way and not be liable to damage.

Another object of the invention is to so construct this device that the stationary contact of the circuit closer may be positioned 35 at a desired distance from the moving contact, thereby permitting energizing of the signal to be controlled and the signal caused to be energized at the proper time and 40 caused to cease operation at the proper time.

Another object of the invention is to provide an improved means for mounting the vibrating or movable contact, this movable contact being carried by springs which extend longitudinally of a tubular carrier and 45 provided at their outer ends with improved means for mounting them.

Another object of the invention is to so construct the mounting means for the outer 50 end portions of the springs that the tension of the springs may be controlled.

Another object of the invention is to so construct this circuit closer that caps which close the end portions of the tubular body 55 may serve to prevent bridging bars which carry the spring-engaging elements from

having movement out of engagement with the end portions of the tubular body.

Another object of the invention is to provide a circuit closer of the character described which will be simple in construction and easy to assemble and to further provide a circuit closer which will not be liable to readily get out of order.

This invention is illustrated in the accompanying drawings, wherein:

Figure 1 is a view showing the improved circuit closer in top plan.

Figure 2 is a longitudinal sectional view through the circuit closer.

Figure 3 is a longitudinal sectional view taken along the line 3—3 of Fig. 2.

Figure 4 is a transverse sectional view taken along the line 4—4 of Fig. 2.

Figure 5 is a sectional view taken along the line 5—5 of Fig. 2, to show the means for mounting the outer portion of one spring.

Figure 6 is a sectional view taken along the line 6—6 of Fig. 2 to show the manner of mounting the outer end of the second spring.

Figure 7 is a view showing the circuit closer applied to a rail.

This improved circuit closer is for use 85 in connection with one of the rails R of a railroad track and is provided with a tubular body 1 which may be formed from a length of metal pipe having its end portions externally threaded to permit caps 2 to be 90 readily put in place and removed. This tubular body is to be clamped to the web of the rail R by means of one or more clamps as shown at C in Fig. 7. From an inspection of this figure, it will be readily 95 seen that when the device is in place, it will be firmly clamped to the web of the rail and therefore when the rail is vibrated by a train passing over the track, the circuit closer will be vibrated with the rail and the 100 device caused to operate as will be herein-after brought out.

The tubular body 1 is provided intermediate its length with an opening 3 to receive a block 4 of hard rubber or any other suitable insulating material. The outer end portion of this block is reduced from opposite sides as shown in Fig. 4 thus providing a neck having flat sides. The flat sided neck passes through a slot formed in the head of the bracket 5 and therefore this bracket 110 which is carried by the tubular body 1 will

serve to prevent movement of the insulating block 4 out of the opening 2 in the tubular body. A contact pin 6 which may be termed a relatively stationary contact passes through 5 an internally threaded sleeve 7 which passes through the block 4, and this threaded stem or contact 6 carries a locking nut 8 so that when the stem has been adjusted to the proper position by turning through the 10 medium of the head 9 at its outer end, the locking nut may be brought into engagement with the outer end of the block 4 and thus serve to securely lock the stem in the desired position. This locking nut may also serve as 15 means for securing a conductor wire 10 forming part of the circuit of any type of electrically operated crossing signal desired. The second wire 11 of the signal may be connected with the tubular body 1 at any 20 suitable point. In the present illustration, this wire 11 has been shown connected with one of the fasteners 12 which serve to secure the bracket 5 to the tubular body.

The movable contact which is to be brought 25 into operative engagement with the inner end of the contact 6 consists of a metal contact 13 mounted intermediate the length of the spring 14 which extends longitudinally 30 of the tubular body 1. One end of the spring is connected with the eye 15 of the pin or 35 stem 16 which carries a bridging bar 17 and is provided at its outer end with a head 18 so that the stem or pin 16 will be prevented from moving out of engagement with the 40 bridging bar 17. The other end of the spring is connected with a tongue 19 provided at its 45 outer end with a side arm or head 30 through which passes a threaded stem or bolt 21. This bolt 21 passes through a bridging bar 50 22 and carries a securing nut 23. It will thus be seen that when the spring is stretched 55 longitudinally of the tubular body and the bridging bars placed to extend transversely of the body with their end portions fitting 60 into the notches or seats 24, the securing nut 23 may be turned to impart longitudinal movement to the bolt 21 and thus permit the 65 springs to be brought to the desired tension.

When this device is in use, it will be connected 70 with the web of one of the rails and as the train moves along the track, the vibration caused by the moving train will cause the movable contact 13 to be vibrated. As the contacts 13 and springs 14 vibrate, 75 the contacts will move into and out of engagement with the inner end of the stationary contact pin 6 thus causing the circuit through the signal to be alternately closed and opened. Therefore, the bell, light or 80 other signal will be properly operated to give warning. If desired, a cap may be provided to enclose the elements positioned externally 85 of the body 1. This cap will be put in place as indicated by dotted lines in Fig. 1 and 90 will preferably be hingedly mounted and

provided with a hasp extension to engage an eye of the pipe so that a lock may be put in place and secure the cap against unauthorized removal.

I claim:

1. A circuit closer comprising a tube, a stationary contact projected into the tube intermediate its length, a movable contact being positioned in the tube and having supporting springs extending longitudinally of the tube, anchoring means for said springs connected with the outer ends thereof and engaged with the end portions of said tube, and means for closing the ends of the tube and retaining said anchoring means in place. 75

2. A circuit closer comprising a tube, a stationary contact projected into the tube intermediate its length, a movable contact positioned in the tube and having supporting springs extending longitudinally of the tube towards the ends thereof, cross bars extending transversely of the tube and having their ends seated in recesses formed in the ends of said tube, means connecting the outer ends of said springs with said cross bars, and caps for the ends of said tube holding said cross bars in said recesses. 90

3. A circuit closer comprising a tube, a stationary contact projected into the tube intermediate its length, a movable contact positioned in the tube, supporting springs for said movable contact extending therefrom towards the ends of the tube, cross bars extending transversely of the tube and having their ends seated in recesses formed in said tube, and stems connected with the outer end portions of said springs and extending through said cross bars, one being provided with a securing nut engaging its cross bar. 100

4. A circuit closer comprising a tube, a stationary contact projected into the tube intermediate its length, a movable contact positioned in the tube, supporting springs for said movable contact extending therefrom towards the ends of the tube, cross bars extending transversely of the tube and having their ends seated in recesses formed in said tube, and means connecting the outer ends of said springs with said cross bars, one of said means being adjustable for placing the springs under desired tension. 115

5. A circuit closer comprising a stationary contact, an elastic member carrying intermediate of its ends a contact located so as to engage said stationary contact when said elastic member vibrates, a supporting member on which said stationary contact is mounted and to which the ends of said elastic member are secured, and means for adjusting said stationary contact towards and away from the normal position of said other contact. 120

6. A circuit closer comprising a tube, a movable contact positioned in the tube and 130

having supporting springs extending longitudinally of the tube, anchoring means for said springs connected with the outer ends thereof and engaged with the end portions of said tube, means for closing the ends of said tube and retaining said anchoring means in place, an insulating sleeve extend-

ing radially of the tube, and a contact adjustable through said sleeve and projecting into the tube for engagement with said movable contact. 10

In testimony whereof I have hereunto affixed my signature.

GEORGE M. BRANT.
